OF D 12,043

No. 12. 043.

Nov. 30. 1880

UNITED STATES PATENT OFFICE.

HENRY HUNT, OF JERSEY CITY, NEW JERSEY, ASSIGNOR TO HARTFORD CARPET COMPANY, OF HARTFORD, CONNECTICUT.

DESIGN FOR CARPET.

SPECIFICATION forming part of Design No. 12,043, dated November 30, 1880.

Application filed September 18, 1880. Term of patent 3½ years.

To all whom it may concern:

Be it known that I, HENRY HUNT, of Jersey City, in the county of Hudson and State of New Jersey, have invented a new and original Design for Carpets, of which the following is a specification.

This invention relates to a new and original design for carpets and similar fabrics; and it consists in the novel grouping and configuration of figures hereinafter more fully described.

The accompanying photograph illustrates a face view of a carpet having my new design.

The figures A A' A² A³ A⁴ A⁵ A⁶ are vine-like branches which extend over the background of the design. Upon these branches appear flowers, leaves, buds, and various other figures.

The figure C is a flower-figure resembling a five-leaved clover.

The figure B is a widely-open flower with projecting stems growing from its center, on the ends of which appear small balls.

The figure D is a tulip-shaped flower.

The figure E is a flower with prominent leaves and projecting stems.

The figure F is a widely-open flower with clearly-defined leaves.

The figure G is a circular ball-like figure surrounded by leaves.

The figure H is a flower-figure with a prominent stem projecting from its center.

The figure I is composed of curving leaves.

The figure J is conical in form, with deeply-cut serrations around the edge.

The figure K is circular and surrounded by closely-set leaves.

The figure L is a conical flower-like figure.

The figure M is a circular flower-like figure with leaves projecting from one side thereof.

The figure N is composed of three leaves bunched together.

I claim—
